UNITED STATES PATENT OFFICE.

HERBERT W. NEUNHERZ, OF COLUMBUS, OHIO, ASSIGNOR TO THE HARVEY MANUFACTURING COMPANY, OF COLUMBUS, OHIO, A CORPORATION OF OHIO.

METAL-FORMING TOOL.

Application filed November 27, 1923. Serial No. 677,282.

To all whom it may concern:

Be it known that I, HERBERT W. NEUNHERZ, a citizen of the United States of America, residing at Columbus, in the county of Franklin and State of Ohio, have invented certain new and useful Improvements in Metal-Forming Tools, of which the following is a specification.

My present invention relates generally to metal bending devices and more particularly to metal bending dies, my object being the provision of a simple economical arrangement capable of use in punch presses and the like for bending rods, strap and like material as for instance in offsetting, hook formation, eye formations as well as other formations of a like character, quickly, uniformly and effectively.

At the present time operations of this nature require forming members, certain at least of which, must rotate, and the formation of the desired bends is thus obviously a more lengthy operation than the quick clean stroke of a punch press which is all that is required according to my improvements.

Moreover the ordinary devices or machines do not provide, or at least do not readily provide, for adjustment so as to change the character of the product, as for instance from a hook and eye. According to my invention it will be seen that such an adjustment is readily provided for by simply varying the stroke of the movable though nonrotatable die.

In the accompanying drawing which illustrates my present invention and forms a part of this specification,

Figure 1 is a side view of a punch press equipped with my improvements,

Fig. 2 is a sectional side view, on an enlarged scale, showing my improvements,

Fig. 3 is a detail side view of the die,

Fig. 4 is a top plan view of the frame and anvil,

Fig. 5 is a sectional side view showing substantially the parts of Fig. 2 with the die lowered in action,

Fig. 6 is a horizontal section taken substantially on line 6—6 of Fig. 2,

Fig. 7 is a plan view of the work, and

Fig. 8 is a sectional side view showing a slightly modified form of anvil.

Referring now to these figures and particularly to Fig. 1 I have shown my im-

provements applied to a known type of punch press 10 wherein the die holding plunger 11 descends in a straight line in operation and is adapted to receive the upper closed end of the cylindrical die 12 proposed by my invention which is adapted to be locked within the plunger 11 as for instance by a set screw 13 shown in Fig. 2.

The die 12, which in accordance with my invention operates by rectilinear movement alone and without rotation, has a hollow body entirely open at its lower end and longitudinally slotted from said lower end for a considerable portion of its length, the body having an approximately straight edge 14 at one side of its slot and a helically curved edge 15 at the other side of its slot. Both of these edges present flat surfaces of the full thickness of the wall of the die, the bore 16 of the latter of which may vary in size and is in use adapted to the size of the cylindrical anvil 17 upstanding from the press frame 18 through an opening 19 through a material support or guide 20.

The material support or guide 20 may have an upstanding guide stud 21 at one side of its opening 19 and is preferably provided with a limiting stud 22 at the opposite side of its said opening in order to thus readily gauge the length of that portion of the material such for instance as rod 23, which should be extended across the anvil 17.

In operation the die descends and, without rotation, engages those portions of the rod 23 at opposite sides of the anvil 17 onto which the die telescopes. The straight edge 14 of the die presses the inner portion of the rod against the guide stud 21 as shown in Fig. 6 while the helically curved edge 15 of the die engages the rod adjacent to its free end and gradually bends the same upon the upper surface of the anvil and in a lateral direction with respect to the movement of the die itself, around a central opening which may be either a centering pin 24 carried by the die and adapted to descend into a centering pin receiving bore 25 of the anvil 17 or a centering pin 26 in the nature of a stud rising axially from the anvil 17 as shown in Fig. 8 and of which stud 26 is an integral part.

It is obvious that in this operation the degree of bending of the free end portion

of the rod 23 depends upon the extent to which the die is lowered it being thus apparent that it is possible to either offset the rod as indicated by the dotted lines A 5 in Fig. 7, bend its free end to various angular positions indicated by the dotted lines B, C and D, form a hook as indicated by the dotted lines E, or form a complete eye as shown in full lines at 27, the latter 10 formation being that resulting from a full downward stroke of the die.

According to the construction shown in Figs. 2, 3 and 5, the centering pin 24 is formed upon the lower portion of and depends from a plunger 28 which slidably 15 interfits the bore 16 of the die and is normally held in its lowermost position, with its limiting shoulder 29 in engagement with an internal shoulder 30 of the die, by a 20 spring 31 which thus permits the plunger with its centering pin to yield upwardly within the die when the lower end of the centering pin 24, which precedes the lower end of the die itself in the downward movement of the latter, reaches the base of the 25 bore 25 of the anvil.

It is furthermore obvious that by the use of the die-carried centering pin the work when completed may be shifted laterally in 30 a single movement from the anvil when the die is raised. While the construction in Fig. 8, wherein the centering pin is integral with and upstands from the anvil itself, requires that the work, if either an eye or a 35 formation closely approximating an eye, be raised vertically off of the stud 26 before it can be freed from the anvil for the introduction of another section of wire or strap.

Thus my invention provides for a bending

operation in a single rectilinear movement 40 of the die without rotation of the latter so that uniform results are assured and speed and economy promoted. My invention also provides for bending in various degrees by simply varying the stroke of the plunger 45 itself.

I claim:

1. A metal bending device including an anvil and a die adapted to telescope the anvil, and a centering pin carried by the die 50 around which the metal is bent on the anvil, said die having a helically curved longitudinal edge avoiding the necessity of rotation in use and said anvil having a bore receiving the said centering pin. 55

2. A metal bending device including an anvil having a bore, a centering pin around which the metal is bent on the anvil adapted to enter said bore, and a hollow bending die 60 adapted to telescope the anvil, said die being lengthwise slotted and having a straight edge at one side of its slot and a curved edge at the opposite side of the slot and said centering pin being movably supported in the hollow of the die. 65

3. A metal bending device including an anvil, a centering pin around which the metal is bent on the anvil, a hollow die adapted to telescope the anvil and having a lengthwise helically curved edge adapting 70 the same for operation without rotation and a centering pin coacting with the anvil and resiliently supported in the hollow of the die. 75

In testimony whereof I have affixed my signature.

HERBERT W. NEUNHERZ.
